Des. 190,871
Patented July 11, 1961

190,871

ROTARY POWER MOWER

John Gale, Carver, and Herbert F. Horner, Minneapolis,
Minn., assignors to Toro Manufacturing Corporation,
Minneapolis, Minn., a corporation of Minnesota

Filed Oct. 7, 1959, Ser. No. 57,844

Term of patent 14 years

(Cl. D40—1)

FIG. 1

FIG. 2.

FIG. 3

FIG. 4

FIG. 1 is a perspective view of a rotary power mower showing our new design;

FIG. 2 is a perspective view thereof as seen from the left side of FIG. 1;

FIG. 3 is a perspective view thereof as seen from the opposite side of FIG. 1; and

FIG. 4 is a top plan view thereof.

The essential features of our design reside in the portions shown in full lines.

We claim:

The ornamental design for a rotary power mower, as shown.
